RESETTING MECHANISM

William H. Robertson, Dayton, Ohio, assignor to
The National Cash Register Company, Dayton,
Ohio, a corporation of Maryland

Original application June 22, 1938, Serial No.
215,131. Divided and this application May 20,
1940, Serial No. 336,182

3 Claims. (Cl. 235—144)

This invention relates to novel mechanism for selectively resetting one or another group of counters to zero.

This application is a division of an application for Letters Patent of the United States, Serial No. 215,131, filed by William H. Robertson and John P. Frank on June 22, 1938, which application has issued on May 6, 1941, as United States Patent No. 2,241,272.

In machines using a plurality of counters it is often desirable to be able to reset certain of the counters to zero without affecting the amounts standing on the remaining counters. To accomplish this end, the resetting mechanism of the instant invention includes an operating lever having two positions. In one position the lever is connected to mechanism operable to reset certain counters, and in the other position it is connected to mechanism operable to reset the other counters.

It is an object of this invention to provide a novel mechanism for selectively resetting counters to zero.

Another object of the invention is to provide means to enforce the completion of a resetting operation involving one set of counters before the selection of another set of counters for resetting can be accomplished.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a view showing the various counters and their arrangement.

Fig. 2 is an elevation showing the counter actuating means, certain parts being omitted for clearness.

Fig. 3 is a side view of the counter resetting mechanism.

Fig. 4 is a front view showing a locking means and a portion of a mechanism controlled by said locking means for preventing operation of the resetting mechanism.

Fig. 5 is a detail side view of the counter reset lever and its connections for selectively operating mechanism for resetting the counters to zero.

Fig. 6 is a detail side view of one of the counter wheels.

GENERAL DESCRIPTION

Described in general terms, the present invention comprises a large number of counters grouped in several different lines conveniently located in the machine with which they are used. Selecting means controlled by the machine cause

the selective operation of the counters to provide an indication of the number of times various operations have occurred in a period of time.

The wheels of each of the counters grouped in a single line are rotatably mounted on a shaft. This shaft has a longitudinal groove cut therein, and the shaft, when rotated, can drive the wheels to zero position by means of pawls on the counter wheels engaging the longitudinal groove.

10 A lever, settable to two positions, has a stud which in one position connects the lever to one of two gears and in another position connects the lever to the other of the two gears to enable the lever to be connected selectively to the gears so 15 that the lever, when operated in either position, will drive the gear connected thereto. Each of these gears is connected to certain of said counter wheel supporting shafts to cause these shafts to be rotated and the counters thereon to be reset to zero.

20 Various interlocking devices are provided to insure that a resetting operation of one group of counters, once it is commenced, will be completed before another group of counters can be reset.

25 The details of these mechanisms will now be described.

DETAILED DESCRIPTION

Special counters

30 The present machine is provided with twenty-one counters (Fig. 1) arranged in four rows or groups, each row including five counters except one row, which has six counters. These rows of counters are disposed in parallel relation with one another in the machine.

35 One row comprises individual clerks' counters, each counter being designated by one of the clerks' letters "A," "B," "D," "E," and "H" corresponding to various clerks' keys bearing the same characters, for adding the number of transactions entered into the machine by each of the clerks.

40 Another row includes individual clerks' item counters, designated as "A item," "B item," "D item," "E item," and "H item," for adding the number of items comprising the various transactions entered into the machine by each clerk.

45 Another row includes "Cash," "Charge," "Rec'd. on acc't.," "Paid out," "No sale," and "Sub-total" counters. These counters each add the total number of transactions of each of the classes above indicated which are entered into the machine by all of the clerks. For example, 50 the cash transactions entered into the machine by each of the clerks will be added into the "Cash" counter.

55 The remaining row comprises "Cash items," "Charge items," "Add," "Customer," and "Total" counters. The "Cash items" counter adds the

number of items comprising all of the cash transactions entered into the machine by the various clerks, while the "Charge items" counter adds the number of items comprising all of the charge transactions entered into the machine by the various clerks. The "Add" counter adds the number of times that the machine is used for adding operations during which no entry is made into any of the classification totalizers. The "Customer" counter adds the total number of complete transactions entered into the machine by all of the clerks, but does not add in certain other adding operations. The "Total" counter adds the number of times that total-taking operations are performed on the machine. The "Sub-total" counter adds the number of times a sub-total operation is performed.

The counters are visible for reading purposes through openings 203 (Fig. 1) in a protecting cover 201, which cover has an integral plate 202 (Fig. 3) protecting the front part of the counter assemblies. A transparent plate 203 lies underneath the cover 201 to prevent unauthorized manipulation of said counters. The counter names and designations are on strips 204 (Fig. 1) beneath the plate 203. The cover 201 and the plate 202 are secured to the counter supporting side frames 189 and 190. These frames are fastened to the base 33 of the machine, the fastening of frame 190 by means of screws 192 being shown in Fig. 3.

The rows of counters, in the order above enumerated, are supported on shafts 210, 211, 212, and 213 respectively (Figs. 2 and 3), which shafts are journaled at their ends in frames 214, 215, 216, and 217 respectively, mounted in side plates 189 and 190.

The construction and operation of the counters herein referred to are old and well known in the art, as illustrated in the Fuller Patent No. 1,394,256, and therefore only a brief description thereof will be given. Since all of said counters are alike in construction except for the number of wheels, some having three wheels and some having four wheels, a detailed description of one counter will suffice for all.

A detailed description of the "Sub-total" counter (Fig. 2) will be given as exemplary of all of said counters. This counter includes a plurality of number wheels 220, each having secured thereto a ratchet 221 mounted on the shaft 212. Also mounted on the shaft 212 is a yoke 222 carrying a pawl 223 mounted on a rod 224 carried by the yoke 222 and spring-urged into engagement with the ratchet 221. This pawl is of the usual multi-tined type and coacts with the ratchets 221 to move the wheels 220 one step of movement when the yoke 222 is rocked counter-clockwise during the operation of the machine. A spring-pressed retaining pawl 225 serves to hold the ratchets 221 and wheels 220 in position. Rocking the yoke 222 counter-clockwise and then clockwise back to its normal position to operate the counter is accomplished through the bifurcated end of a lever 226 embracing a rod 227 mounted in the yoke 222.

The counter-clockwise movement of the yoke 222 causes the pawl 223 to advance the lowest order wheel 220 one step. Each ratchet 221 has a deep notch 228, and, as its associated wheel 220 passes from "9" to "0", the tine of the pawl 223 for said wheel enters said notch 228, thus permitting the pawl 223 to be rocked counter-clockwise about the rod 224, whereupon the next higher order pawl-tine turns its associated wheel one

step. The levers 226 are selectively operable to cause the counters to be actuated. The selective operation of the levers forms no part of this invention and will not be described herein. For these details reference may be had to the parent case.

Counter reset mechanism

The counters in the first two rows (Fig. 1) are identified with individual clerks, whereas the counters in the other two rows, except the total and sub-total counters, are each identified with transactions involving any of the clerks. It is sometimes desirable—for example, where the clerks work on different shifts—to reset the individual clerk counters when changing shifts, and at the same time keep as a running total the amounts on the counters identified with the clerks in general. For this purpose the machine is provided with a single reset lever 380 common to all of the counters and adapted to be first manually moved counter-clockwise or forward to perform a resetting operation, and then clockwise or rearward to return it to its home position. This lever has two positions of adjustment, a lower position and an upper position. In its lower position the lever 380 is adapted to reset the two rows of individual clerk counters, while in its upper position it is adapted to reset the other two rows of counters except the total and the sub-total counters.

Referring particularly to Fig. 3, the shafts 210 and 211, which rotatably support the counter wheels 220 of the individual clerks' counters, have secured thereto pinions 382 and 383, respectively, while the shafts 212 and 213, which rotatably support the wheels 220 of the transaction and customer counters, have secured thereon pinions 384 and 385, respectively. The pinions 382 and 383 mesh with an idler gear 386 freely mounted on a stud 387 in the frame 190, while the pinions 384 and 385 mesh with an idler gear 388 freely mounted on a stud 389 carried by the frame 190. The gears 386 and 388 mesh with gears 390 and 391, respectively (Fig. 5), both loosely mounted on a stud 392 in the frame 190.

The gear 386 (Fig. 3) and its associated gear 390 are located on one side of a spacer plate 393 mounted on the studs 387 and 389, while the gear 388 and its associated gear 391 are located on the opposite side of said plate 393. The plate 393, therefore, serves to keep the proper sets of gears in alignment and said pairs of gears in non-interfering relation.

Each of the shafts 210 to 213, inclusive, is provided with the usual groove 394 (Fig. 6), which is adapted, when said shafts are rotated counter-clockwise, to coact with a spring-pressed reset pawl 395 carried by each counter wheel 220 to reset said wheel to zero. The reset lever 380, when in its lower position of adjustment, is adapted to actuate the gear 390 to cause the shafts 210 and 211 to be rotated counter-clockwise to reset to zero the counter wheels 220 supported thereon. When the lever 380 is in its upper position of adjustment, it is adapted to actuate the gear 391 to cause the shafts 212 and 213 to be rotated counter-clockwise to reset the counter wheels 220 supported thereon. The means by which the lever 380 selectively actuates the gears 390 and 391 to reset the various groups of counter wheels 220 will now be described.

The lever 380 is so arranged that manual movement thereof forward, or counter-clockwise, effects the resetting to zero of two rows of

counters simultaneously, the two rows of counters thus reset being dependent upon the position in which said lever is adjusted. The lever 380 (Figs. 3 and 5) has a slot 400 and surrounds the stud 392 to slide and pivot thereon. Also pivotally mounted on the stud 392 is a disk 401 having slots 402 which receive studs 403 on the lever 380 and guide said lever from one position of adjustment to another.

On the opposite side of the lever 380 is mounted a stud 404 adapted to selectively connect said lever 380 with either one of the gears 390 or 391. This is accomplished by means of the stud 404 coacting with irregularly-shaped slots 405 and 406 in the gears 390 and 391, respectively, which slots are concentric with the stud 392. The slots 405 and 406 terminate at their right-hand ends in radial offset portions 407 and 408, respectively.

When the lever 380 is in its lower position of adjustment, the stud 404 engages the offset portion 407 of the slot 405 to connect said lever 380 with the gear 390, thus enabling the lever 380 to drive the gear 390 counter-clockwise to reset to zero the individual clerks' counters on the shafts 210 and 211. When the lever 380 is shifted to its upper position of adjustment, the stud 404 engages the offset portion 408 of the slot 406, thereby connecting said lever 380 with the gear 391, thus enabling the lever 380 to drive the gear 391 counter-clockwise to reset to zero the transaction counters on the shafts 212 and 213. When one or the other of the gears 390 or 391 is driven by the lever 380, through the engagement of the stud 404 with one of the offset portions 407 or 408 in said gears, the stud 404 will ride idly in the concentric portion of the slot 405 or the slot 406 of the other one of said gears which is not driven.

When the lever 380 has been moved the full extent of its forward stroke, it is then manually returned to its home position. When this occurs, the stud 404 returns whichever one of the gears 390 or 391 with which it is connected to its normal position.

Means is provided for preventing movement of the lever 380 out of its adjusted position after it commences its resetting movement and until it is returned to its home position. This means consists of a circular plate 414 (Fig. 5) with a guide rail 415 concentric with the stud 392 and fastened to the frame 190. The rail 415 has an opening 416 opposite a stud 417 on the lever 380 when said lever is in its home position. Shifting of the lever 380 to either of its positions of adjustment will place the stud 417, through the opening 416, on one side or the other of the guide rail 415. When the lever 380 is moved out of its home position, the stud 417 will ride on whichever side of the rail 415 it has been positioned on and will thus prevent any movement of the lever 380 out of its adjusted position during a resetting operation.

A full stroke device is provided for locking the lever 380 against reverse movement when traveling in either direction until the stroke has been completed. This device consists of a two-armed pawl 420 (Fig. 3), which, by means of a slot 421 surrounding a stud 422 mounted in the frame 190, is slidably and pivotally mounted on said stud. A retaining pawl 423, pivoted on a stud 424 in the frame 190, serves to maintain the pawl 420 in cooperative relation with teeth 425 of the disk 401. The pawl 423 is constantly urged clockwise by a spring 426 connected to a stud 427 in the pawl 423 and to a stud 428 in the frame 190.

The pawl 420 is normally held in the position shown in Fig. 3 by the retaining pawl 423, a forward edge 429 of which is caused, by the spring 426, to bear against the right side of a nose 430 of the pawl 420, thus tending to rotate the pawl 420 clockwise and also to retain the right end of the slot 421 against the stud 422. The clockwise movement of the pawl 420 causes a nose 431 thereof to ratchet in and out of the teeth 425 when the lever 380 is moved counter-clockwise.

As the lever 380 and disk 401 approach the end of their counter-clockwise movement, a finger 432 on the disk 401 will strike the nose 431 and slide the pawl 420 to the right on the stud 422. This sliding movement of the pawl 420 cams the retaining pawl 423 against the action of the spring 426 until the apex of the nose 430 of the pawl 420 passes the apex of the angle formed by the side 429 and another side 433 of the retaining pawl 423, whereupon the retaining pawl 423 is free to rock clockwise to bring the side 433 into contact with the left side of the nose 430 of the pawl 420.

This results in the pawl 420 being cammed counter-clockwise about the stud 422, which at this time is seated in the left end of the slot 421. Such counter-clockwise movement of the pawl 420 withdraws the nose 431 out of cooperative relation with the teeth 425 and throws a nose 434 of the pawl 420 into cooperative relation with the teeth 425.

Upon return clockwise movement of the lever 380, the nose 434 of the pawl 420 ratchets in and out of the teeth 425 until the lever 380 reaches its home position, whereupon a finger 435 on the disk 401 coacts with the nose 434 and rocks said pawl 420 clockwise to the position shown in Fig. 3, wherein the nose 431 again becomes engaged with the teeth 425 on the disk 401.

Locking means for total lever and counter reset lever

The total lever 54 is adapted to be manually moved downward from its normal or Add position, as shown in Fig. 4, to three separate positions of adjustment for conditioning the machine to perform three different kinds of total-taking operations, said positions being designated by the numbers 1, 2, and 3. When the lever 54 is moved to the No. 1 position, it conditions the machine for item total-taking operations; in the No. 2 position it conditions the machine for taking totals from the clerks' totalizers; and in the No. 3 position it conditions the machine for taking totals from the transaction totalizers.

Locking means is provided for normally locking the lever 54 out of its Nos. 2 and 3 positions of adjustment. The lever 54 is always free to be moved from its normal or Add position to its No. 1 or item total-taking position for the purpose of taking totals of multiple-item transactions. In addition to the function of locking the lever 54 out of its Nos. 2 and 3 positions of adjustment, said locking means performs another function; namely, locking the counter reset lever 380 against operation when the total lever 54 is locked out of the above-mentioned positions. Inasmuch as only this last-named function is pertinent to the present invention, a description of this function only will be given herein.

Said locking means consists of a lock 440 (Fig. 4) adjacent the total lever 54 and mounted on a total lever frame 441. This lock 440 is adapted, when a key is inserted therein, to operate a bolt

442 provided with a bar 443 and a lug 444. The bar 443 coacts with the lever 54 to lock it out of the positions above mentioned, while the lug 444 operates mechanism to lock the counter reset lever 380 against operation. The lug 444 has a slot 445 engaged by a pin 446 on an arm 447 of a link 448. The arm 447 is pivoted to an arm 449 pivoted on a stud 450 in the frame 441. The link 448 is pivoted to a locking lever 451 pivoted on a stud 452 (Fig. 3) in the frame 196. The lever 451 has a hook 453 which engages over the upper end of an arcuate plate 454 fast to the disk 401 to lock said disk and its associated reset lever 380 against operation. The plate 454 also serves to guide the hook 453 and the lever 451 when the disk 401 and the reset lever 380 are being operated, and to prevent the locking lever 451 from being moved to locking position when the reset lever 380 is out of its home position.

It will be seen from the above that when the lock 440 is operated by a key to move the bolt 442 to the right, as viewed in Fig. 4, it will, through the slot and pin connection 445—446, lower the link 448 to rock the lever 451 clockwise to disengage the hook 453 from the plate 454, thus releasing the disk 401 and the reset lever 380 for operation.

When it is desired to reset the counters to zero, the manager or some other authorized person unlocks the lock 440 (Fig. 4), thereby moving the link 448 downward to rock the lever 451 (Fig. 3) clockwise to release the counter reset lever 380 for operation. The lever 380 is then manually moved to the full extent of its forward stroke to reset to zero two of said rows of counters, after which the lever is returned to its home position. If the lever 380 is in its lower position of adjustment, it will cause the two rows of individual clerks' counters to be reset to zero, but if said lever has been manually shifted to its upper position, it will cause the two rows of transaction counters to be reset to zero.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described, a plurality of groups of counters; a plurality of shafts, one for each group of counters and having means thereon to reset the counters associated therewith; a pair of coaxial gears; means connecting one of said gears to certain of said shafts and the other of said gears to the remaining shafts; a manipulative device shiftable to a plurality of positions adjacent said gears; and a projection on said device selectively cooperable with one or the other of said gears depending upon the position of the device, to connect the device to the gears so that they may be selectively operated thereby.

2. In a machine of the class described, the combination of a plurality of counters; a plural-

ity of reset shafts upon which said counters are mounted; a support; a pair of gears coaxially mounted on said support, the body portion of each gear containing a notch and an adjacent slot; a manipulative device mounted for rotation about said support and for shifting movement to either of two positions relative to said support; a stud on said device cooperable with the notches in one or the other of said gears when the device is in either of its shifted positions, said notches and slots in said gears being so located that when the stud is in the notch of one gear it rides in the slot of the other gear, thus forming a selective operating connection between said gears and said device whereby the shifting of the device will connect one of the gears to the device and the rotation of the device about the support will operate the connected gear; and means connecting one of said shafts to one of the pair of gears 10 and another of the shafts to the other of said gears, thus affording a selective reset of the counters.

3. In a machine of the class described, the combination of a plurality of counters; a plurality of reset shafts upon which said counters are mounted; a support; a pair of gears coaxially mounted on said support, the body portion of each gear containing a notch and an adjacent slot; a manipulative device mounted for movement from and back to a normal position and for shifting movement to either of two positions relative to said support while in said normal position; a stud on said device cooperable with the notches in one or the other of said gears when the device is in either of its shifted positions, said notches and slots in said gears being so located that when the stud is in the notch of one gear it rides in the slot of the other gear, thus forming a selective operating connection between said gears and said device whereby the shifting of the device will connect one of the gears to the device and the rotation of the device about the support will operate the connected gear; means connecting one of said shafts to one of the pair of gears and another of the shafts to the other of said gears, thus affording a selective reset of the counters; full-stroke means associated with said manipulative device and effective, when the device is moved from normal position, to compel a complete movement of the device from and back to normal position; a projection on said manipulative device; and a member fastened to said support and cooperable with the projection on the manipulative device whenever the manipulative device is out of normal position to thereby prevent the shifting of the manipulative device after it has been moved from normal position and until it is returned to normal position, said member fastened to the support and the cooperating projection on the device operating in conjunction with the full-stroke means to compel the completion of a resetting operation involving a selected group of counters before the other group of counters can be selected for a resetting operation.

WILLIAM H. ROBERTSON.
